CLAIM

The ornamental design for a connector assembly, as shown and described.

DESCRIPTION

FIG. 1 is a perspective view of a connector assembly.

FIG. 2 is a top plan view according to FIG. 1.

FIG. 3 is a bottom plan view of FIG. 1.

FIG. 4 is a front elevational view of FIG. 1.

FIG. 5 is a rear elevational view of FIG. 1.

FIG. 6 is a first side elevational view of FIG. 1; and,

FIG. 7 is a second side elevational view of FIG. 1.

The broken lines illustrate environmental supplementary structure of the connector assembly and form no part of the claimed design.
